FLUSH TANK BULB OR VALVE

Joseph C. Burnes, Eddystone, Pa.

Application October 3, 1934, Serial No. 746,738

1 Claim. (Cl. 4-56)

The invention relates to a flush tank bulb or valve and more especially to a resilient or elastic flush ball valve for a flush tank.

The primary object of the invention is the provision of a bulb or valve of this character, wherein in the same when seated to shut off the discharge of water from the flush tank will be devoid of water content and on the lifting of this bulb or valve the same will float until the admission of water content thereto, whereupon it becomes weighted under the influence of the water content to effect a positive and sure seating thereof and also for quick action.

Another object of the invention is the provision of a bulb or valve of this character, wherein the construction thereof is such as to eliminate the sticking of the same on the valve seat and also that will be prevented from being pushed aside from water rushing in from the water supply and other causes resultant in the failure of the valve to properly function or operate, the valve being provided with a pilot or a tip functioning to guide the valve properly to its seat, particularly when the said valve or bulb has been lifted for the discharge of the water from the flush tank and at the same time eliminating side washing of the valve by the water currents from the water supply to the tank.

A further object of the invention is the provision of a valve or bulb of this character which has a piston principle where the velocity of the water and the weight of the water are employed to close the valve, while the pilot or tip to said valve or bulb guides it in position for seating and proper seating action thereto.

A still further object of the invention is the provision of a valve or bulb of this character which is simple in its construction, positive of operation, thoroughly reliable and efficient in its working, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a central vertical section on an enlarged scale showing the valve or bulb constructed in accordance with the invention unseated from the valve seat.

Figure 2 is a top plan view, the valve rod being in section.

Figure 3 is a sectional view on the line 3-3 of Figure 1 looking in the direction of the arrows.

Similar reference characters indicate corresponding parts throughout the several views in the drawing.

Referring to the drawing in detail, the bulb shown is of suitable yielding material, for example, rubber, and comprises a hollow main body 5 having the substantially semi-spherical shaped lower portion 6 and a convexed top 7 provided with a central vertically disposed boss 8. Embedded within the boss 8 is a metallic nut or 10 inwardly threaded sleeve 9 in which is tapped the hanger or operating rod 10 and the latter has connection with a manual control (not shown) for the lifting of the valve to unseat the same for the discharge of water from a flush tank, a portion thereof being indicated at 11, while the seat for the valve or bulb is indicated at 12.

The valve or bulb body 5 at the lower semi-spherical portion 6 has joined therewith an inverted substantially conical-shaped guide pilot 25 or tip 13 through the medium of a contracted neck 14 centrally located in alignment with the longitudinal center axis of said valve or bulb and this pilot or tip is of hollow formation and in communication with the body 5 through the 30 passage 15 in the neck 14 and has embedded in the larger area of its body a wire mesh reinforcement 16 to avoid collapsing of the pilot or tip.

The extreme point of the pilot or tip 13 is 35 provided with a water discharge port or opening 17, while the body 5 at the lower portion 6 thereof, close to the neck 14, has provided therein air escape ports 18. The tip or pilot 13 cooperates with the seat 12 for the valve or bulb to guide the 40 same and to prevent displacement by water currents from the water supply to the tank. The valve or bulb under its construction will be relieved of sticking on the side of the valve seat and also from being pushed aside from water 45 rushing into the tank 11 from a water supply, or other causes.

When the control is actuated, it being understood, of course, that the valve is normally seated, the same is pulled from the valve seat 12 and 50 the pilot or tip being submerged in the water causes the said valve or bulb to become filled with water through the port 17 as air rushes out through the ports 18. When water in the tank has almost run out, the rushing of the 55

water out of the tank acts upon the pilot or tip 13, causing the valve to be pulled downwardly onto the seat in a piston-like manner, and the water content of the valve gives weight thereto 5 to assure velocity action for the seating of said valve. When the valve becomes seated, the water content is liberated through the port 17, so that the valve when free of its content will have floating action on the lifting thereof from 10 its seat for the discharging of the water from the tank.

The construction and manner of operation of the valve or bulb should be apparent from the

foregoing description and, therefore, a more extended explanation has been omitted for the sake of brevity.

What is claimed is:

A flush tank bulb comprising a hollow semi-spherical shaped body having a convexed top, a hollow pilot tip having an opening at its apex and a tubular neck joining the pilot with the said body in spaced relation to each other and establishing communication therebetween, the body being formed with openings concentrically 5 with respect to said neck. 10

JOSEPH C. BURNES.
